UNITED STATES PATENT OFFICE.

EDWARD EVERETTE HARTSELL, OF ROWLAND, ALABAMA, ASSIGNOR OF ONE-THIRD TO ISAAC FOX DELONY, OF SAME PLACE.

WAGON-BED.

SPECIFICATION forming part of Letters Patent No. 594,621, dated November 30, 1897.

Application filed April 21, 1897. Serial No. 633,205. (No model.)

To all whom it may concern:

Be it known that I, EDWARD EVERETTE HARTSELL, a citizen of the United States, residing at Rowland, in the county of Limestone and State of Alabama, have invented certain new and useful Improvements in Wagon-Beds; and I do hereby declare the following to be a full, clear, and exact description of the invention, such as will enable others skilled in the art to which it appertains to make and use the same.

This invention relates to wagons and similar vehicles; and the object in view is to provide extension-sides for a wagon-body and to mount these sides in such a manner that they will interlock with each other, requiring the sides to be removed in a certain order in order that they may successively release each other.

20 The detailed objects and advantages of the invention will be pointed out in the course of the subjoined description.

The invention consists in certain novel features and details of construction hereinafter specifically set forth, illustrated in the drawings, and incorporated in the claims hereto appended.

In the accompanying drawings, Figure 1 is a plan view of a wagon-body constructed in accordance with the present invention. Fig. 2 is a side elevation of the same. Fig. 3 is a rear end view. Fig. 4 is a front end view. Fig. 5 is a detail section through one corner of the wagon-body in line with the extension-sides. Fig. 6 is a similar section taken at the junction of the sides and ends of the main body of the wagon. Fig. 7 is a detail perspective view of one of the socket-pieces or keepers. Fig. 8 is a detail perspective view showing the brake-lever and its engaging rack. Fig. 9 is a detail vertical section showing the manner of locking the front and rear extension-boards.

Similar numerals of reference designate corresponding parts in all the views.

Referring to the drawings, 1 designates the bottom of an ordinary wagon box or body provided with stationary sides 2. These sides are connected to the bottom by means of bolts 3, which pass through the bottom, the upper ends being flattened and provided with coun-

tersunk openings to receive screws or other suitable fasteners 4, which enter or pass through the sides 2, the lower ends of the bolts passing through transverse bars 6 under 55 the wagon-body and receiving nuts 7. The stationary sides 2 may thus be removed in an emergency by detaching the nuts 7 and drawing the sides upward. Any number of securing-bolts 3 may be employed. The upper 60 portions of the rear bolts 3 are rabbeted, as indicated at 8, in their front edges to receive L-shaped plates 9, secured to the rear side of the tail-gate 10. In front of the tail-gate are arranged flanged keeper-plates 11, with which 65 other plates 9 on the front of the tail-gate engage when the tail-gate is slid downward vertically between the sides 2. The front board 12 is secured in place in a similar manner and may be readily removed whenever 70 desirable.

The extension-sides are indicated at 13 and may be of any suitable height. Each of said sides is provided upon its outer surface with a series of oblique standards 14, secured 75 thereto by screws or other fasteners 15, arranged at intervals. The lower ends of the standards extend below the bottom edge of the side 13 and are adapted to enter keepers or socket-pieces 16, also arranged at an oblique angle and extending at right angles to the inclination of the standards 14. In order to place the extension-sides 13 upon the body of the vehicle, the lower ends of the standards 14 must be entered in the socket-pieces 16 and the boards must then be slid 80 downward at an angle corresponding to the inclination or obliquity of the standards 14.

Upon their inner sides and adjacent to the front and tail boards the extension-sides 13 are provided with spaced cleats or keeper-plates 17 for engagement with L-shaped plates 18 at the ends of the front and rear extension-boards 19 and 20, respectively. The front extension-board 20 has secured to its outer 95 surface a vertical standard 21, which is extended downward sufficiently to pass through an opening 22 in the bottom 1 and also through the front cross-bar 6, said standard being provided at a point below the bar 6 with a transverse opening 23 to receive a cotter or split pin, which will prevent the upward movement 100

of said standard and hold the extension-board 20 in place. A similar standard 24 is provided for holding the tail extension-board in place. The tail-board 19 is provided at its rear with 5 a hook 25, adapted to receive a pivoted loop 26, mounted on the end rung 27 of a ladder 28, the side bars 29 of which are pivotally connected to the rear end of the wagon-body, as indicated at 30, so that said ladder may be 10 folded upward or downward, according as the same is required. The engagement between the hook 25 and loop 26 also serves to prevent the displacement of the tail extension-board 20.

15 In order to remove the extension-sides 13, the front and rear extension-boards 19 and 20 must first be slid vertically out of place, for the reason that when said boards are in place the sides 13 cannot be removed, as it is necessary to slide said sides upward in an oblique line, which movement is defeated by the front and rear boards when in place, said front and rear boards thus serving to lock the sides. In placing the extension-boards upon 25 the body of the wagon the sides 13 must first be placed in position and the end pieces subsequently inserted.

31 designates a rock-shaft mounted transversely under the bottom of the wagon-body 30 and in suitable bearing-sleeves 32, secured thereto. This rock-shaft constitutes the brake-beam and is provided with bent ends 33, to which suitable brake-shoes 34 are secured and arranged to contact with the wheels. 35 At one side of the wagon-body the shaft 31 is provided with a crank-arm 35, from which a brake-rod 36 extends forward and connects pivotally to the lower end of a brake-lever 37, pivotally mounted intermediate its ends 40 at 38 in a suitable hanger 39, attached to one of the stationary side-boards 2 of the body.

40 designates a toothed rack which is secured to the side 2 near its upper edge, said rack being constructed from a strip or bar of 45 metal bent into U shape, as shown, and having its end portions secured to the wagon-body. The central or outlying portion of the rack is incised, as shown at 41, and the upper edge bent inward to form a horizontally-disposed flange 42, which is notched or toothed, 50 as indicated at 43. The lever 37 is provided upon its outer surface with a longitudinally-extending rib 44, which is adapted to engage between the teeth or in the notches of the 55 rack when adjusted and be thereby held at any desired adjustment. The lever 37 is mounted loosely on its fulcrum, so that it may be rocked laterally into and out of engagement with the rack. This brake mechanism is extremely simple in construction, 60 reliable in operation, and will not interfere

with the detachability of the extension-sides of the wagon.

Having thus described the invention, what is claimed as new, and desired to be secured 65 by Letters Patent, is—

1. The combination with the body of a wagon or similar vehicle, of extension-sides made removable in an oblique line, substantially as described. 70

2. The combination with the body of a wagon or other vehicle, of extension-sides having obliquely-disposed standards, and socket-pieces secured to the said body and adapted to receive said standards, substantially as 75 described.

3. The combination with the body of a wagon or other vehicle, of an extension-side, a series of oblique standards secured rigidly to said extension-side and having their lower 80 ends extended below the bottom edge of the extension-side, and keepers or socket-pieces secured to said body and adapted to receive the lower ends of the standards, substantially as described.

4. The combination with the body of a wagon or other vehicle, of extension-sides provided with oblique standards adapted to be received in socket-pieces on the body whereby the extension-sides are caused to move in oblique planes, and removable end-boards slidingly fitted between the extension-sides and movable in vertical lines, substantially as 90 described.

5. The combination with the body of a 95 wagon or other vehicle, of extension-sides provided with oblique standards adapted to enter socket-pieces on the body whereby the sides are made movable in oblique lines, and extension end-boards slidingly mounted in 100 ways between the extension-sides and movable in a different direction from the direction in which the sides move, substantially as described.

6. The combination with the body of a 105 wagon or other vehicle, of extension-sides mounted thereon, extension front and rear boards slidingly engaging the sides and serving to lock the same against displacement, and standards secured to the end-boards and 110 removably fitted in openings in the bottom of the body, said standards having provision beneath the bottom of the body for preventing their displacement, substantially as described.

In testimony whereof I have signed this specification in the presence of two subscribing witnesses.

EDWARD EVERETTE HARTSELL.
